UNITED STATES PATENT OFFICE.

JAMES W. CLARK, OF ETNA, OHIO.

TELEPHONE.

SPECIFICATION forming part of Letters Patent No. 258,891, dated June 6, 1882.

Application filed February 13, 1882. (No model.)

To all whom it may concern:

Be it known that I, JAMES WILLSON CLARK, a citizen of the United States, residing at Etna, in the county of Licking and State of Ohio, have 5 invented new and useful Improvements in Telephones, of which the following is a specification.

My invention relates to improvements in telephones in which the vocal line is connected at each end with the diaphragm of a receiving and 10 transmitting instrument, and in which a call is operated mechanically by means of the vocal line.

The objects of my invention are to provide 15 for relieving the diaphragms, when the telephone is not being used, of the strain due to the tautness of the vocal line; to cut off the sound communication of the diaphragms or to suspend their functions to receive and transmit sound whenever the telephone is not being 20 used, and at the same time maintain the connections of the vocal line with the instruments for the purpose of making a call from either instrument by the vibration of the line independent of the diaphragms.

25 In acoustic telephones, so far as I know and can find, the tension of the vocal-line wire has always been upon the diaphragms, giving them a permanent concave set, rendering them less sensitive to sound. Moreover, as hitherto used, 30 the vocal line is subject to more or less contraction and expansion, and therefore requires frequent adjustment to maintain a proper taut connection with the diaphragms. With such taut connection the diaphragms produce a hissing 35 or a singing noise under the action of the wind. These objections are overcome by my invention, which embraces means for producing a slack in the connection of the vocal line with the diaphragm or diaphragms, and therefore 40 by suspending the functions of the diaphragms at one or both ends of the vocal line while practically maintaining their connection with said line. The direct connections of the line are with pivoted levers or other means adapted 45 for effecting the call from either end of the vocal line without affecting the connection of the line with the diaphragms, whereby the diaphragm of one or both instruments can be adjusted in slack connection with the line, so that 50 no communication can take place and no conversation be heard until the signal has been

given and the diaphragms of both instruments put in taut connection with the vocal line.

Referring to the accompanying drawings, Figure 1 represents a front elevation of the 55 transmitting and receiving instrument of a telephone embracing my improvements; Fig. 2, a vertical sectional view of the same, showing the diaphragm in slack or non-communicating connection with the vocal line; Fig. 3, 60 a similar view, showing the diaphragm in taut or communicating connection with the vocal line; Fig. 4, a vertical section taken on the line x x of Fig. 2; Fig. 5, a side elevation, showing the signal device in connection with 65 its operating-lever; Fig. 6, a similar view, showing the signal device disconnected from its operating-lever. Fig. 7 shows the call-bell side, and Fig. 8 a horizontal section taken on the line y y of Fig. 3, showing the device for 70 holding the speaking and hearing part in taut relation to the vocal line.

The instrument is composed of a fixed case, a , within which a mouth and ear part, b , is fitted to slide, having the diaphragm c , to which 75 the vocal-line wire d is connected by a flexible section. The fixed part is a box of any suitable form secured to the wall or other place, and carries the signal device. The mouth and ear part b is adapted to have a limited horizontal sliding movement within the fixed part, and the latter for this purpose is open at its front side, while the cover of the movable part forms also the cover b' of the fixed part. The movable part is preferably formed of a block of 80 wood with a central opening forming the speaking and hearing orifice e , the inner end of which is closed by the diaphragm. I prefer to make the central opening, e , cylindrical, and to attach the diaphragm to the back of the 85 block b , so as to leave a narrow space, e' , communicating with the central opening, e , the diaphragm c covering the full area of the block, but attached to it only around its edges, as shown in Figs. 2 and 3, so as to give freedom 90 for vibration. The narrow space e' between the solid end of the block and the diaphragm serves to receive the sound-waves with their full effect upon the diaphragm. The movable mouth and ear part b , when set fully within the 95 fixed case, leaves a chamber therein back of the diaphragm to allow of the arrangement in 100

said case of a signal-operating lever. This lever *f* is preferably arranged in vertical position, is pivoted at its upper end to the fixed case, and, passing through the chamber in the back part of said case, is connected at its lower end to the signal-operating device. The lever and the back of the fixed case are provided with openings for the line *d*, coincident with the center of the speaking and hearing orifice.

10 The vocal line is connected at each end by means of an eyed button, *g*, to the lever *f* of each instrument, the tension of said line being borne directly by said levers and the buttons resting thereon. The line-wire is connected 15 by these buttons *g* to buttons *g'* of the diaphragms *c* by means of a short section of silk, cotton, or other flexible cord, *h*, so as to allow of the movements of the speaking and hearing parts to make their connection with the line. 20 wire slack or taut. The button *g* has no fixed connection with the lever *f*, and the flexible cord-section *h* is attached to said button, so that when drawn taut it practically forms a part of the line-wire, and the strain of the latter may be borne entirely by the diaphragms 25 when the speaking and hearing part is drawn outward from the fixed case by the person desiring to communicate, as shown in Figs. 3 and 8. This adjustment, however, is not made 30 until the call has been made through the line and while the flexible section is in a slack condition, as shown in Fig. 2, and the tension of the line is upon the button-connection with the lever.

35 The lower end of the lever *f* projects sufficiently below the fixed case to form a handle, with which the call device is connected, and which is constructed in such manner as to impart the vibratory movements of the lever to 40 a bell-hammer or other sounder. As shown, this device consists of a rod, *i*, secured in vertical position to the fixed case, having its lower end, *i'*, bent or cranked and connected to a plate, *j*, on the handle end of the lever, and 45 having its upper end, *i''*, similarly bent, and carrying the bell-hammer *i'''* by a spring-arm, *i'''*, in position to strike the bell *k*, the extent of the vibration of which arm is adjusted by a set-screw, *l*, secured in a bracket on the case, 50 so that the hammer will always strike the bell when the line is vibrated.

A spring, *m*, is arranged in the case to support the lever *f* under the tension of the line. To vibrate the line to make the call it is only 55 necessary to place the thumb or finger upon the lower end of the lever and press it back in the direction of the line, and, compressing the spring *m*, let the thumb or finger slip off, when the force of the spring will cause the lever *f* to 60 fly back, and thus give a sudden pull upon the line-wire, vibrate the lever at the other instrument, and give a distinct ring of the bell to call the person with whom conversation is desired. The person thus making the call can 65 detach the hammer-rod *i* from the lever *f* of his instrument, if he desires to make a call,

without ringing the bell at his instrument. This is effected by raising the bell-hammer carrying rod *i* so as to detach its lower cranked end, *i'*, from the lever-connection *j*, as shown 70 in Fig. 6, so that the vibration of the lever *f* will not give the signal to the person making the call if he so desires to cut it off. The call having been made, the operator at once draws out the speaking and hearing part *b* of his instrument 75 to place its diaphragm in taut connection with the line, when the conversation can take place; the operator at the other end of the line having also put his instrument in taut connection with the line. 80

The cover of the speaking and hearing part is provided with handles *n n*, by which it is drawn outward to adjust the telephone for communication, and set back to relieve the diaphragm of the tension of the vocal line. As 85 it is necessary to hold the speaking and hearing part when drawn outward to maintain the taut relation of its flexible cord-section *h* with the line, I utilize the handle *n n* as holds for this purpose, although any suitable holding 90 device may be provided. When the handles are thus used they pass through the cover of the hearing and speaking part, and may be pivoted thereto, and they extend within the case, preferably at the corners thereof, a suffi- 95 cient distance to form ratchet-pawl *r r*, adapted to take into ratchet-racks *s s*, fixed to the inside walls of the fixed case. The relation of these ratchet-handles to the fixed racks is such that in drawing out the speaking and hearing 100 part the inner ends of the ratchet-arms will move over the ratchet-teeth of the fixed racks and take into them by pressing the handles toward each other, and thus hold the movable part so as to put and maintain its diaphragm 105 in taut relation with the line-wire. When the conversation is over the holding-arms are released from the racks by pressing the handles from each other, there being sufficient play of the handles in the cover to allow of such holding and releasing function of their inner ends, as 110 shown by dotted lines in Fig. 8. The handles are connected to the speaking and hearing part *b*, so as to be fixtures with it, drawing it out and setting it back, and yet be under the 115 control of the operator as to their holding and releasing functions. The extent of the movement of the hearing and speaking part is from two to four inches, to give the required slack in its connection with the line-wire. When 120 the speaking and hearing part is set back, as in Fig. 2, the strain of the vocal-line wire is entirely upon the lever *f* of the signal device; but when the movable part *b* is drawn out the strain of the vocal-line wire is upon the dia- 125 phragm, as shown in Figs. 3 and 8.

I claim--

1. In an acoustic telephone, the diaphragm of the speaking and hearing part, connected with the vocal line by a short section of cord of some suitable flexible material, in combination with the signal-operating lever, a sustain-

ing-spring therefor, and a fixed part or case within which the said speaking and hearing part is adapted for adjustment to render the said diaphragm connection slack or taut in relation to the vocal line, substantially as described, for the purpose specified.

2. The combination, in an acoustic telephone, of a fixed part or case and the vocal line with an adjustable speaking and hearing part, a short cord or flexible section connecting it with the vocal line, a pivoted device connected with the said fixed part or case and the vocal line, and a sustaining-spring for said pivoted part, substantially as herein set forth, for the purpose specified.

3. In an acoustic telephone, the transmitting and receiving instrument, composed of a fixed part or case and an adjustable speaking and hearing part having the diaphragm, the latter being connected to the vocal line by a short flexible cord-section and adapted to be set toward and from the end of the vocal line to render the said flexible section slack or taut in relation to said vocal line, substantially as described, for the purpose specified.

4. The combination, in an acoustic telephone, of the fixed part or case, the vocal line, and means for connecting it with said fixed part or case with the adjustable speaking and hearing part, the flexible cord-connection of the diaphragm with said vocal line, and means for operating said speaking and hearing part and holding the same when set in taut connection with the vocal line, substantially as described, for the purpose specified.

5. In combination, in an acoustic telephone, the fixed part or case *a*, the adjustable speak-

ing and hearing part *b*, having the diaphragm *c*, the vocal line *d*, the signal-operating lever *f*, its supporting-spring *m*, the flexible cord-section *h* of the line, the signal device, and means for operating and holding the adjustable part in relation to the fixed part, substantially as described, for the purpose specified.

6. The combination, in an acoustic telephone, of the fixed part or case *a*, the adjustable speaking and hearing part *b*, having the diaphragm *c*, the flexible cord-section *h*, the lever *f*, its supporting-spring *m*, the line *d*, and the signal device, with the handles *n n*, forming the ratchet-pawl *r r*, and carried by said adjustable part, and the racks *s s*, carried by said fixed part, substantially as described, for the purpose specified.

7. The combination, in an acoustic telephone, of the line *d*, the lever *f*, and the line-button *g*, having a non-fixed relation to said lever, with an adjustable speaking and hearing part, a supporting-spring, *m*, for said lever, and a signal device operated by said lever.

8. In an acoustic telephone, the combination of the line and means for supporting it independent of the diaphragm with an adjustable carrying part for the diaphragm and a short cord-section connecting said diaphragm with the line, substantially as described, for the purpose specified.

In testimony whereof I have hereunto set my hand in the presence of two subscribing witnesses.
